HEAT EXCHANGE APPARATUS

Charles H. Leach, Roselle, N. J.

Application April 7, 1934, Serial No. 719,502

7 Claims. (Cl. 257—223)

The present invention relates to heat exchange apparatus for the refining and condensation of hot oil vapor, and is more particularly concerned with apparatus of this type designed for the employment of relatively high pressures on the cooling liquid side.

The purpose and object of the invention is to improve heat exchange apparatus of the tubular type in a manner to safeguard the construction when employed with high pressure cooling liquid, and to accomplish this result without defeating the efficiency of the apparatus or substantially increasing the difficulty incident to dismantling and replacement or tightening of the tubes. With this and other objects in view, I have replaced the usual cover member connected to the base for detachably closing the liquid passages by a series of smaller cover members, each serving to seal a liquid space, and each engaging with the base in such a manner that pressure within the space tends to increase sealing engagement. In connection with the use of these members, I have also modified and changed the complementary features of the apparatus, together with the path of cooling liquid flow, to maintain the desired efficiency of heat exchange without substantially lowering the efficiency.

In a simple and efficient form of the invention embodying this principle, I provide a circular base which is divided essentially by ribs into four quadrant-shaped liquid spaces. Each of these liquid spaces communicates with the tubular cooling system through a series of quadrant-shaped floating heads, the floating heads being staggered with respect to the liquid spaces through an angle of approximately 45° in order that the liquid flow shall pass from a fluid space into the cooling tubes, thence through the floating head, at which it is reversed and returned to the next adjacent quadrant liquid space; in other words, the flow being progressive and reversed at opposite ends of the tubular system by the liquid spaces and floating heads, respectively. The liquid spaces or passages are free from partitions or the like except for that space at which cooling liquid enters the exchanger, this space being conveniently divided by a mid-partition, the cooling liquid entering at one side of the partition and being withdrawn therefrom at the opposite side of the partition. This entrance and exit space is more conveniently sealed by an external bolted-on cover which, due to its comparatively small area and freedom from distortion stresses because of this fact, may be tightly sealed without danger of leakage. In the accompanying drawings illustrating the preferred form of the invention, Fig. 1 represents a section in elevation of a heat exchanger embodying the features of the invention, with one bank of tubes shown therein, the remaining banks being omitted for purposes of clarity; Fig. 2 is a bottom

plan view of the heat exchanger shown in Fig. 1; Fig. 3 is a section upon the line 3—3 of Fig. 1, looking in the direction of the arrows; Fig. 4 is a section upon the line 4—4 of Fig. 1; and Fig. 5 is a section upon the line 5—5 of Fig. 1.

The heat exchanger shown in the illustrated embodiment of the invention is provided with a circular base member 10, which may be in the form of a casting, forging or the like, this base member having an upstanding circumferential flange 12 which surrounds and provides one or more condensate basins. The integral transverse web 14 forming a part of the base provides a tube sheet into which are connected at their lower ends a series of cooling tubes 16, as will be evident. At the opposite side of the tube support the base provides a series of cooling liquid spaces or passages. These are formed by a depending circumferential flange 18, which in conjunction with intermediate cross-ribs 20 and 22, as indicated more particularly in Fig. 2, form a series of four quadrant-shaped chambers bounded by the circumferential flange 18. These quadrant-shaped chambers are each closed by a detachable cover member designed to seal the chambers during the operation of the exchanger. Cooling liquid is admitted through an inlet nozzle 24 and removed through an outlet nozzle 26, the two nozzles being formed in the flange 18 adjacent to one another, and handling the cooling liquid from opposite sides of a single quadrant space divided by a mid-partition 28, as shown particularly in Fig. 3.

In the present construction the cooling liquid is caused to flow progressively through the tubular system in eight successive passes, which may be designated for purposes of description as A to H, inclusive. The first pass indicated as A, communicates with the inlet chamber, and after passing through the cooling tubes is reversed at the opposite end by a floating head which directs the cooling liquid into the second pass of tubes B. These tubes communicate at their lower ends with a portion of the next succeeding quadrant space, as indicated in Fig. 3, which serves to redirect the liquid into the succeeding pass C, where the operation is repeated.

From a comparison of Figs. 3 and 4, which show sections, respectively, above and below the tube sheet, it will be evident that the tube quadrants are staggered with respect to the liquid quadrants approximately 45° so that each floating head quadrant straddles two succeeding liquid passages at the opposite end of the system, and in a like manner each quadrant liquid passage straddles each two succeeding floating heads, so that the floating heads and the liquid passages in the base each serve to bridge one another for the successive and continuous flow of the cooling liquid.

This method of construction will be evident from a comparison of Figs. 3, 4 and 5, where the ribs 20 and 22 providing the quadrant liquid passages below the tube sheet are shown in their proper relationship to the tube bank quadrants, which are divided as indicated generally by the dotted sections 30 and 32, these quadrants again being shown in Fig. 4. Only two vapor passes are provided by a single central partition 36, which 5 extends upwardly lengthwise of the shell, with two quadrant tube banks upon each side. The enclosing shell may be formed in two parts, a lower portion 40 including the vapor inlet and outlet nozzles 42 and 44, and an upper portion 10 46 having a domed head 48 formed integral therewith by welding or otherwise. The two sections are bolted to one another through flanges 50 and to the base through bolting flanges 52, as indicated in Fig. 1.

20 The quadrant-shaped floating heads are indicated at 54, and may be of usual construction comprising a base portion 56 into which the tube ends are rolled, and a detachable cover portion 58 bolted thereto, the arrangement of the floating head quadrants being shown more particularly in Fig. 5.

30 The base member may be and preferably is divided by the section ribs 30 and 32 into four quadrant-shaped condensate basins, each having a domed surface to shed condensate therefrom, and each provided with a condensate drain 60, as indicated in Fig. 4.

35 The liquid passages formed in the base member and subjected to high pressure cooling liquid are closed by quadrant-shaped cover members 62, each of which is provided with a sealing shoulder 64 resting upon an inwardly extending supporting ledge 66 formed at the lower end of the flange 18. Due to the shape of the opening in the chamber, the cover members may be inserted therein 40 and then assembled with the shoulder resting on the ledge in sealing position. Sealing engagement is secured by a series of holding or clamping yokes 68, each provided with a holding bolt 70 threaded into the cover, and each engaging at 45 its opposite ends with the supporting flange 18 and ribs 20 or 22. The joint between the cover and flange may be provided with a sealing gasket 72.

50 With this construction the securing bolts are not called upon to resist the pressure thrust within the chamber which merely tends to force the covers in tighter engagement with the seats and increase sealing engagement. This method of construction is satisfactory for sealing three of the four quadrant chambers where no partition rib is required, and where accordingly the covers may be inserted through the openings in the bottom of the chambers. At the entrance and exit 55 60 chamber, however, provided with the mid-rib 28, it is desirable to use a single external bolted cover, and this is accordingly illustrated in Figs. 1 and 2, the cover having the general contour of the chamber and being flat, as indicated at 65 70 75. This flat cover is bolted externally to the flange and cross ribs through bolting connections 77. The cover and flange may be also provided with cooperating tongue and groove 78 to enhance sealing engagement. Due to its relatively small size, the problem of externally sealing this joint, even under substantial pressures, is not serious, particularly as the circumferential flange 18 in conjunction with the cross ribs 20 and 22 adequately brace and reinforce the base member 80 85 90 95 100 105 110 115 120 125 130 135 140 145 150 against distortion due to the pressures.

The term "base" as employed in the specification and claims is intended to define a member constituting a support for the tubes independently of the manner or direction in which the tubes project therefrom. For example, inversion 80 of the unit with a series of tubes depending from an upper support would not alter its function as a tube support or base member.

What is claimed is:

1. Heat exchange apparatus comprising a supporting base, radially disposed ribs to form liquid spaces, a tubular cooling system connected with the base and communicating with the spaces, and a detachable cover member for at least one of the spaces seating with the pressure against the base. 85 90

2. Heat exchange apparatus comprising a circular base member having a circumferential flange and radial ribs to provide separate liquid sectors, a separate cover member for each sector detachably connected with the base, and a tubular cooling system communicating with the liquid sectors. 95

3. Heat exchange apparatus comprising a circular base, radial partitions dividing the base into liquid sectors, cooling tubes communicating with each sector, a series of floating head sectors connected with opposite ends of the cooling tubes, each floating head sector bridging two successive sectors at the opposite ends of the cooling tubes, 100 and a series of individual cover sectors connected to the base and sealing the passages. 105

4. Heat exchange apparatus comprising a base, a peripheral flange, generally radial partitions to provide separate liquid sectors in conjunction with the flange, a series of internally supported cover members for the sectors, cooling tubes communicating with the sectors, and floating heads at the opposite ends of the tubes each bridging two successive sectors. 110

5. Heat exchange apparatus comprising a base, a peripheral flange, generally radial partitions to provide separate liquid sectors in conjunction with the flange, a series of internally supported cover members for the sectors, cooling tubes communicating with the sectors, floating heads at the opposite ends of the tubes each bridging two successive sectors, liquid inlet and outlet nozzles communicating with one of the sectors, and means for separating the sector in communication therewith into separate chambers. 120 125

6. Heat exchange apparatus comprising a base, a peripheral flange, generally radial partitions to provide separate liquid sectors in conjunction with the flange, a series of internally supported cover members for the sectors, cooling tubes communicating with the sectors, floating heads at the opposite ends of the tubes each bridging two successive sectors, liquid inlet and outlet nozzles communicating with one of the sectors, means for separating the sector in communication therewith into separate chambers, and a cover member externally connected to the inlet and outlet sector. 130 135

7. Heat exchange apparatus comprising a base member of circular conformation, a series of cooling liquid sectors formed at one side of the base member, cooling tubes connected to the base and communicating with the sectors, floating head sectors at the opposite ends of the cooling tubes 140 145 150 staggered with relation to the sectors and each bridging two successive cooling liquid sectors, and means for sealing the cooling liquid sectors in the base.
